(57) CLAIM

The ornamental design for a jumpsuit, as shown and described.

DESCRIPTION

FIG. 1 is a perspective view of a jumpsuit, embodying my new design;

FIG. 2 is a front elevation view thereof;

FIG. 3 is a rear elevation view thereof;

FIG. 4 is a first side elevation view thereof;

FIG. 5 is a second side elevation view thereof;

FIG. 6 is a top plan view thereof; and,

FIG. 7 is bottom plan view thereof.

The portions of the figures illustrated in broken lines are provided for illustrative purposes only and form no part of the claimed design. The contrast in shading represents a contrast in appearance and does not represent any particular color, material, texture or finish.

1 Claim, 6 Drawing Sheets
